Attorney.

UNITED STATES PATENT OFFICE.

HENRY F. BELCHER, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,970, dated December 7, 1897.

Application filed November 1, 1897. Serial No. 657,104. Term of patent 14 years.

To all whom it may concern:

Be it known that I, HENRY F. BELCHER, a citizen of the United States, residing at Chicago, in the county of Cook and State of Illinois, have invented certain new and original Designs for Prism-Lights, of which the following is a specification.

My invention relates to designs for prism-lights.

10 Figure 1 is a plan view of a prism-light embodying my invention. Fig. 2 is a cross-section therethrough.

15 A is the body of the prism-light; B, one side thereof; C, a series of prisms thereon; D, a series of broken or chipped prisms.

As illustrated in the drawings, the fractured or broken prisms present a series of

somewhat regularly-distributed, but irregularly-bordered, recessed, or hollowed-out surfaces. The work is called "fracto-work," 20 and the appearance may be described as that of a series of rain-drops stretched along in regular rows.

The essential features of my design are found in a prism-light comprising a substantially flat thin body with a series of mutilated prisms on one side thereof. 25

I claim—

A design for a prism-light, substantially as shown and described.

HENRY F. BELCHER.
